UNITED STATES PATENT OFFICE.

MICHAEL J. BRIERTY, OF CHICAGO, ILLINOIS.

ELECTRICALLY-CONTROLLED MECHANISM.

Application filed September 11, 1922. Serial No. 587,468.

To all whom it may concern:

Be it known that I, MICHAEL J. BRIERTY, a citizen of the United States, residing at Chicago, in the county of Cook and State of Illinois, have invented a new and useful Improvement in Electrically-Controlled Mechanism, of which the following is a specification.

My invention relates generally to electrically controlled mechanism and more particularly to heat controlling apparatus having an electric controlling circuit; and my primary objects are to provide improved electrically controlled mechanism and to provide improved electrically controlled means for regulating the temperature of the atmosphere in a room or the like.

Referring to the accompanying drawings, Figure 1 shows, by a vertical broken sectional view, a building supplied with a heater or furnace equipped with draft and check doors or dampers controlled by electrical apparatus embodying my invention. Figure 2 is a plan view of the main portion 25 of the electrical apparatus forming a part of the structure shown in Fig. 1. Figure 3 is a view in side elevation of the apparatus shown in Fig. 2; and Figure 4, a view of the electrical apparatus, shown diagrammatically with parts removed, together with a circuit controlling thermometer, this view illustrating the circuit connections.

My improved apparatus is designed to be used preferably in conjunction with a circuit-making-and-breaking thermometer whereby electrical connections with the apparatus may be established and broken under the influence of changes in temperature of the atmosphere surrounding the thermometer and thus the source of heat supplied may be regulated to maintain approximately even temperature.

My improved apparatus, as shown, comprises a frame shown as formed of side plates 5 and 6 extending parallel with each other and held together by transversely extending bolts 7, passing therethrough, with spacers 8 surrounding the bolts and interposed between the plates, and an electric motor 9 secured to the plate 6, as by the bracket 10, and provided on its armature-carrying shaft 11 with a pinion 12, which meshes directly with the gear 13 of a train of gears 13, 14, 15, 16, 17, 18 and 19 supported on the shafts 20, 21, 22 and 23 suitably journaled in the plates 5 and 6, one

end of the shaft 23, where it extends beyond the plate 5, being provided with a crank arm 24. The opposite end of the shaft 23 is provided with a metallic head 60 25 presenting radiating divergent arms 26 and 27 provided with brushes 28 and 29 respectively, which extend from these arms in the same direction and generally parallel with the shaft 23, the brush 29 being located 65 at a greater distance from the shaft 23 than the brush 28. The brush 28 cooperates with a pair of metallic segments 30 and 31 secured to the outer face of a disk 32 of insulating material rigidly secured to the shaft 70 23. The segments 30 and 31 are secured to this disk to be out of contact with each other, as shown in Fig. 3, and are so positioned that in the rotation of the shaft 23, these segments will be successively moved 75 across and in contact with the outer end of the brush 28. The brush 29 cooperates with a metal ring 33 secured to the outer face of the disk 32 and out of contact with the segments 30 and 31, this ring being so positioned that in the rotation of the shaft 23, the brush 29 will remain constantly in contact therewith.

The apparatus also involves a vertically disposed solenoid 34 secured to the plate 6 by means of a bracket 35, the lower end of this bracket having a lateral extension 36, which projects beneath the vertical central opening of the solenoid. The core of the solenoid is represented at 37 and when the solenoid is deenergized, the core rests upon the bracket extension 36. The core 37, the upper end of which is preferably of reduced diameter, as represented at 38, cooperates 80 with a contact-making-and-breaking device 95 formed of a movable contact member 39, which is preferably formed of a strip of flexible metal, as for example copper, secured to a bracket 40 on the plate 5 and insulated therefrom; and a pair of contact arms 41 and 42 preferably of spring strip metal, which are located above and below, respectively, the movable contact 39 for alternating engagement with the latter. The contact strips 41 and 42 are rigidly secured 100 to a bracket 43 carried by the plate 6 and insulated therefrom and from each other by insulation as shown.

In Fig. 1, the apparatus is shown as applied to a furnace 44 located in a basement 110 and supplying heat to a room above it. The furnace illustrated has a check door 45 and

a draft door 46 connected together by a chain 47, extending over pulleys 48 and 49 journaled on the furnace structure, the length of the chain 47 being such as to cause 5 one door to be open when the other is closed. The apparatus shown in Figs. 2 and 3 would be supported in any desirable manner adjacent the furnace, with its crank arm 24 connected with the chain 47, as indicated, for 10 drawing the latter up and down and opening and closing the doors 45 and 46, as hereinafter described. The room above the basement is shown to contain an electric thermometer 50, which may be of any suitable type, the one shown in Fig. 4 being 15 of a desirable construction and comprising three contact points 51, 52 and 53, extending into the path of the mercury contained in the bulb 54 and tube 55 of the thermometer, 20 the contact points 51, 52 and 53 being connected, respectively, with buttons 56, 57 and 58 insulated from each other. The thermometer also comprises a movable contact-finger 59 pivoted at 60 and adapted to be 25 swung into engagement with any one of the buttons 56, 57 and 58.

The electrical connections between the parts described and the thermometer and the source of current supply are as follows: 30 The two wires, through which current is supplied to the apparatus, are represented at 61 and 62, the wire 61 being connected with the movable contact 39 and also with one of the terminals 63 of the solenoid 34. The 35 wire 62 connects, by a wire 64, with one of the terminals of the motor 9 and, by a wire 65, with the contact-finger 59. The other terminal of the motor connects, by a wire 66, with the ring 33. The segment 31 connects, by a wire 67, with the contact strip 41 and the segment 30 connects, by a wire 68, with the contact strip 42. The other terminal of the solenoid 34 connects, by a wire 69, with the mercury in the bulb 54.

45 The operation of the apparatus is as follows: Assuming the contact-finger 59 of the thermometer to be in contact with the button 57, as shown, and the mercury in the bulb 54 and tube 55 to have just made connection with the contact 52, an electric circuit is established through the solenoid 34 by way of the wires 62 and 65, contact-finger 59, button 57, contact point 52, the mercury, wires 69 and 63 and wire 61 with the result 50 of elevating the core 37 of the solenoid and lifting the other end of the contact member 39 out of engagement with the contact strip 42 and into engagement with the contact strip 41, the outer, free, end of the member 55 55 flexing upwardly at the portion thereof beyond the contact 41. This results in closing the circuit through the motor 9 through the following described circuit: wires 62 and 64, motor 9, wire 66, ring 33, arms 26 and 60 65 27 to segment 31 (the head 25 being in a

position diagrammatically opposed to that shown in Fig. 4), wire 67, contact strip 41, contact strip 39 and thence to the wire 61. In this condition of the parts, the draft door 46 is open, and the check door is closed, and 70 the operation of the motor 9, by establishing the circuit just described, operates to rotate the shaft 23 throughout one-half of a revolution, thereby closing the draft door 46 and opening the check door 45. The current 75 through the motor 9 is automatically arrested upon its rotating the shaft 23 throughout one-half of a revolution, by the movement of the short arm 26 of the head 25, in rotating in clockwise direction in Fig. 80 4, out of engagement with the segment 31, namely, the position shown in Fig. 4, it being observed that this short arm when the motor stops is in engagement with the segment 30. 85

As long as the mercury of the thermometer is in engagement with the contact 52, the solenoid 34 remains energized and the motor 9 remains at rest. As soon, however, as the mercury descends out of engagement with the contact 52, the circuit through the solenoid 34 is broken, whereupon its core 37 descends, permitting the contact 39 to disengage from the contact 41 and engage with the contact 42, whereupon the motor 9 is 90 again operated to rotate the shaft 23 one-half of a revolution, with the result of opening the draft door 46 and closing the check door 45; the circuit connections by which the motor is thus energized being as follows: from wire 62 to wire 64, motor 9, wire 66, ring 33, arm 27, arm 26, segment 30, wire 68, contacts 42 and 39 to wire 61. The rotation of the shaft 23 throughout one-half of a revolution from the position shown 100 in Fig. 4, as stated, operates to move the short arm 26 of the head 25 out of engagement with the segment 30 and into engagement with the segment 31, thereby breaking the circuit through the motor 9 and so 105 positioning the parts that as soon as the contact 39 is moved into engagement with the contact 41 through the energizing of the solenoid 34, by means of the mercury engaging the contact 52, a circuit will be established through the motor 9 for operating it as above stated, these various alternating operations continuing throughout the use 110 of the apparatus and serving to maintain a substantially uniform temperature in the room supplied with heat from the furnace, it being understood that by providing a plurality of contact points for engagement with the mercury at different levels, the operator may set the apparatus to maintain 115 any desired temperature. 120

It will be readily understood from the foregoing that the apparatus is operatively simple and reliable in operation; one of the desirable features of the apparatus being 130

that of providing the flexible contact strip 39. This feature is of advantage where alternating current is used, as during the period of energizing the coil 34 the contacts 5 39 and 41 will not become separated in the alternations of the current and thus arcing is prevented.

While I have illustrated and described a particular construction embodying my invention, I do not wish to be understood as intending to limit it thereto, as the same may be modified and altered without departing from the spirit of my invention.

What I claim as new and desire to set 15 cure by Letters Patent, is:

1. The combination with a source of electric current, of an electric motor, a shaft driven from the motor, a contact-making-and-breaking device constructed and arranged to make and break circuit under changes in the temperature of the atmosphere surrounding it, a solenoid controlled by the position of said device, the core of said solenoid being operated in one direction 20 when the solenoid is energized and automatically movable in the opposite direction when the solenoid is de-energized, a second electrical contact device actuated by said core, and a third electrical contact device 25 actuated from said motor and the flow of current to which is controlled by said second contact device, said second and third contact devices being constructed and arranged to intermittently direct the current 30 from said source through the motor to produce partial successive rotations of said shaft in the same direction under variations in temperature of the atmosphere surrounding said last-referred-to device.

40 2. The combination with a source of electric current, of an electric motor, a shaft driven from the motor, a contact-making-and-breaking device constructed and arranged to make and break circuit under changes in the temperature of the atmosphere surrounding it, a solenoid controlled by the position of said device, the core of said solenoid being operated in one direction 45 when the solenoid is energized and automatically movable in the opposite direction when the solenoid is de-energized, a second electrical contact device actuated by said core and comprising a pair of spaced contacts and a third contact movable from one 50 to the other of said pair of contacts in the movement of said core in opposite directions, and a third electrical contact device actuated from said motor, said second and third contact devices being constructed and arranged to intermittently direct the current from said source through the motor to produce partial successive rotations of said shaft in the same direction under variations in temperature of the atmosphere surrounding said last-referred-to device.

55 3. The combination with a source of electric current, of an electric motor, a shaft driven from the motor, a contact-making-and-breaking device constructed and arranged to make and break circuit under changes in the temperature of the atmosphere surrounding it, a solenoid controlled by the position of said device, the core of said solenoid being operated in one direction 60 when the solenoid is energized and automatically movable in the opposite direction when the solenoid is de-energized, a second electrical contact device actuated by said core, and comprising a pair of spaced contacts and a third resilient contact movable from one to the other of said pair of contacts in the movement of said core in opposite directions, and a third electrical contact device actuated from said motor, said second and third contact devices being 65 constructed and arranged to intermittently direct the current from said source through the motor to produce partial successive rotations of said shaft in the same direction under variations in temperature of the atmosphere surrounding said last-referred-to device.

70 4. The combination with a source of electric current, of an electric motor, a shaft driven from the motor, a contact-making-and-breaking device constructed and arranged to make and break circuit under changes in the temperature of the atmosphere surrounding it, a solenoid controlled by the position of said device, the core of said solenoid being operated in one direction 75 when the solenoid is energized and automatically movable in the opposite direction when the solenoid is de-energized, a second electrical contact device actuated by said core and comprising a pair of spaced contacts and a third resilient contact member located between said pair of contacts and extending beyond the latter at which portion it is engaged by said core, said resilient contact member being movable from one to the other of said pair of contacts in the movement of said core in opposite directions, and a third electrical contact device actuated from said motor, said second and third contact devices being 80 constructed and arranged to intermittently direct the current from said source through the motor to produce partial successive rotations of said shaft in the same direction under variations in temperature of the atmosphere surrounding said last-referred-to device.

85 5. The combination with a source of electric current, of an electric motor, a shaft driven from the motor, a contact-making-and-breaking device constructed and arranged to make and break circuit under changes in the temperature of the atmosphere surrounding it, a substantially vertically disposed solenoid controlled by the po 90

sition of said device, the core of said solenoid being lifted when the solenoid is energized and descending to normal position when the solenoid is de-energized, a second electrical contact device actuated by said core, and a third electrical contact device actuated from said motor and the flow of current to which is controlled by said second contact device, said second and third contact devices being 10 constructed and arranged to intermittently direct the current from said source through the motor to produce partial successive rotations of said shaft in the same direction under variations in temperature of the atmosphere surrounding said last-referred-to device.

6. The combination with a source of electric current, of an electric motor, a shaft driven from the motor, a contact-making- 20 and-breaking device constructed and arranged to make and break circuit under changes in the temperature of the atmosphere surrounding it, a second contact device, electrical operated means for actuating 25 said second device controlled by said first-named contact device, and a third contact device actuated from said motor and comprising a ring of current-conducting material, segments of current-conducting material insulated from each other and from said ring and a contact element cooperating with said ring and segments, said ring and segments and said contact elements cooperating therewith being relatively rotatable, the said second and third contact devices being constructed and arranged to intermittently direct the current from said source through the motor to produce partial successive rotations of said shaft in the same direction under va-

riations in temperature of the atmosphere 40 surrounding said last-referred-to device.

7. The combination with a source of electric current, of an electric motor, a shaft driven from the motor, a contact-making-and-breaking device constructed and arranged to make and break circuit under changes in the temperature of the atmosphere surrounding it, a substantially vertically disposed solenoid controlled by the position of said device, the core of said solenoid being lifted when the solenoid is energized and descending by gravity to normal position when the solenoid is de-energized, a second electrical contact device comprising a pair of spaced contacts and a third contact 50 located between and movable into engagement with said pair of contacts alternately, said third contact in the normal position of said core engaging one of said pair of contacts, and a third electrical contact device actuated by said motor and comprising a ring of current-conducting material, segments of current-conducting material insulated from each other and from said ring and a contact element cooperating with said ring and segments, said ring and segments and said last-referred-to contact cooperating therewith being relatively rotatable, said ring being in circuit with said motor and said segments being in circuit respectively with the said pair 60 of contacts, the whole being constructed and arranged to intermittently direct the current from said source through the motor to produce partial successive rotations of said shaft in the same direction under variations in 70 temperature of the atmosphere surrounding said last-referred-to device.

MICHAEL J. BRIERTY.
